UNITED STATES PATENT OFFICE.

HARRY M. ACRY, OF PITTSFIELD, MASSACHUSETTS, ASSIGNOR TO
STANLEY ELECTRIC MANUFACTURING COMPANY, OF PITTS-
FIELD, MASSACHUSETTS, A CORPORATION OF NEW JERSEY.

INSULATOR.

No. 824,055.

Specification of Letters Patent.

Patented June 19, 1906.

Application filed November 12, 1904. Serial No. 232,464.

To all whom it may concern:

Be it known that I, HARRY M. ACRY, a citizen of the United States, residing at Pittsfield, county of Berkshire, State of Massachusetts, have invented certain new and useful Improvements in Insulators, of which the following is a specification.

My invention relates to insulators for electric conductors; and its object is to provide a novel form of insulator adapted for supporting bus-bars and other heavy conductors, which is simple, strong, and compact, which may be quickly applied and removed, and which is adapted to receive conductors of different sizes.

My invention will best be understood by reference to the accompanying drawings, in which—

Figure 1 shows a side elevation of an insulator arranged in accordance with my invention; and Fig. 2 shows an end elevation of the same.

In the drawings, A represents a suitable support adapted to receive the weight of the conductors, and which I have shown as a section of pipe or metal tubing.

B represents a U-shaped bolt, with its base twisted to form a loop in a plane at an angle to the plane of the U, this loop being of a size to fit closely around the pipe A, which lies in the plane of the U.

D represents an insulating-block, of porcelain or other suitable material, which is provided on its lower surface with a V-shaped groove adapted to engage the pipe A and is provided on its sides with grooves adapted to engage the legs of the U-shaped bolt. When the bolt is placed in position around the pipe and the block D is slipped over the bolt into the position shown, the block and bolt lock each other in position ready to receive the conductor. The block D is provided on its upper surface with a groove at right angles to that on its lower surface, adapted to receive the bus-bar or other conductor C.

E represents a second porcelain block or cap, also provided with lateral grooves adapted to be engaged by the ends of the U-shaped bolt and having on its lower surface a V-shaped groove adapted to engage the conductor C.

b b represent nuts carried on the extremities of the U-shaped bolt, by means of which the clamp E may be clamped in position.

By tightening these nuts the conductor C is firmly clamped between the insulating-blocks D and E.

What I claim as new, and desire to secure by Letters Patent of the United States, is—

1. In an insulator, a U-shaped bolt having its base bent out of the plane of the U to engage a support lying in the plane of the U, two detachable insulating-blocks having lateral grooves adapted to be engaged by the legs of said U-shaped bolt, and clamping means at the ends of said bolt.

2. In an insulator, a U-shaped bolt having its base bent to form a loop in a plane at an angle to the plane of the U; two detachable insulating-blocks having lateral grooves adapted to be engaged by the legs of said bolt, and clamping means at the ends of said bolt.

3. In an insulator, a U-shaped bolt having its base bent out of the plane of the U to engage a support, an insulating-block having lateral grooves adapted to slide on the legs of said bolt and having a groove on its under surface adapted to engage said support, a second insulating-block also having lateral grooves, and clamping means at the ends of said bolt engaging said second block.

4. In an insulator, a U-shaped bolt having its base bent to form a loop in a plane at an angle to the plane of the U, an insulating-block provided with lateral grooves adapted to be engaged by said bolt and having grooves on its lower and upper surfaces at right angles to each other adapted respectively to engage a support and to receive a conductor, a second insulating-block having lateral grooves and a groove on its lower surface adapted to engage the conductor, and clamping means at the ends of the bolt engaging said second block.

5. In an insulator, a U-shaped bolt having its base bent out of the plane of the U to engage a support lying in the plane of the U, two detachable insulating-blocks having lateral grooves adapted to be engaged by the legs of said bolt and having V-shaped grooves on their adjacent surfaces, and clamping means at the end of said bolt.

In witness whereof I have hereunto set my hand this 10th day of November, 1904.

HARRY M. ACRY
